UNITED STATES PATENT OFFICE.

LEONARD W. SEBRING, OF MOLINE, ILLINOIS.

DESIGN FOR A STATUE, STATUETTE, OR ORNAMENT.

55,574.

Specification for Design. Patented June 29, 1920.

Application filed December 22, 1919. Serial No. 346,798. Term of patent 7 years.

To all whom it may concern:

Be it known that I, LEONARD W. SEBRING, a citizen of the United States, residing at Moline, in the county of Rock Island and State of Illinois, have invented a new, original, and ornamental Design for a Statue, Statuette, or Ornament, of which the following is a specification, reference being had to the accompanying drawing, forming part thereof.

The figure is an elevation of a statue, statuette, or ornament, showing my design.

I claim:

The ornamental design for a statue, statuette, or ornament, as shown.

LEONARD W. SEBRING.
